UNITED STATES PATENT OFFICE

FREDERICK W. LAENCHER, OF ELMHURST, NEW YORK, ASSIGNOR TO A. KIMBALL COMPANY, OF NEW YORK, N. Y., A CORPORATION OF NEW YORK

PRICE TAG

Original application filed March 13, 1929, Serial No. 346,538. Divided and this application filed November 6, 1930. Serial No. 493,731.

This invention relates to price tags, and has for an object the provision of improvements in this art.

The nature and object of the invention will be best understood by reference to a specific embodiment of the invention which will now be described, this embodiment being also illustrated in the accompanying drawing, in which, the figure is a perspective view of a 10 gang strip of price tags embodying the invention.

This application is filed as a division of Laencher application, Serial No. 346,538, filed March 13, 1929, entitled Tickets and apparatus for printing them. The said application describes a machine for printing and severing individual tags from a gang strip such as illustrated herein, and as explained in the said application, the said strip cooperates 15 functionally with the feed mechanism in order to secure proper intermittent feed of individual tag lengths. The said gang strip may also cooperate functionally with the feed mechanism of other types of printing and 20 severing machines, such, for example, as that illustrated in Laencher application, Serial No. 451,222, filed May 10, 1930, entitled Printing apparatus.

The said gang tag strip, designated generally by numeral 1, is formed from a suitable length of paper or cardboard having any desired dimensions, and, if desired, individual tag lengths 2 may be indicated by rounded portions 3, which, when individual tags are 25 severed from the strip as contemplated in the two machines previously referred to, provides neatly rounded corners for the individual tags.

The individual tickets ordinarily require 30 some attaching or securing means for fastening to the goods to be marked, staples or strings being commonly used. In the preferred embodiment illustrated, staples 4 are secured to the individual tags closely adjacent the edges thereof, the prongs 5 of the 35 said staples extending approximately perpendicular to the plane of the tickets and being arranged in a line parallel to the edge of the strip. It will be observed that the rounded portions 3 form cusps, the apices 3' of

which extend inwardly beyond the line of the staples.

In order that the said strips may be fed properly by machines such as those heretofore referred to it is also desirable to provide accurately spaced means for engagement by a suitable part of the feeding mechanism, and for this purpose, in the preferred embodiment illustrated, the strip is provided with severed portions, preferably in the form of slits 6, extending inwardly from the clear or unstapled edge of the strip toward the stapled edge, thus placing the slits away from the staples or other attaching means so as to prevent interference by such attaching means with the feeding mechanisms of the previously referred to printing and severing machines. As will be understood, the said slits 6 meet the apex of the adjacent rounded corners as illustrated in the drawing. 70

It will be understood that the invention may be variously modified and embodied within the scope of the subjoined claims.

I claim as my invention:

1. A gang price tag strip comprising a 75 series of tags provided with attaching means at one edge and partially severed from each other by slits made from the other edge, and extending inwardly beyond the medial line of the strip to provide abutments for engagement by feeding mechanism.

2. An article of manufacture comprising a strip divided into equal tag widths by aligned cusps along the opposite edges of the strip, an attaching device secured to each tag, the said devices having prongs arranged in alignment along one edge of the strip, and slits between each two tags at the other edge. 85

3. A price tag strip comprising a series of tags provided with attaching staples at one edge and partially severed from each other by slits made at a distance back of the staple bearing edge and extending to the other edge of the strip, uncut material being left between the slit and the staple bearing edge. 90

4. An article of manufacture comprising a strip divided into equal tag lengths by aligned cusps along the opposite edges of the strip, attaching staples along one edge of the strip having aligned prongs, said cusps 100

along the stapled edge of the strip extending inwardly beyond the line of prongs, and slits between the tags extending inwardly from the points of the cusps along the un-
5 stapled edge toward the points of the cusps along the stapled edge of the tag, said slits providing abutments for engagement by feeding mechanism.

In testimony whereof, I have signed my
10 name to this specification this 5th day of
November, 1930.

FREDERICK W. LAENCHER.
